United States Patent Office

Des. 183,535

Patented Sept. 16, 1958

183,535

AIR CONDITIONING CABINET

Herman A. Mugler, Huntington, N. Y.

Application May 10, 1957, Serial No. 46,104

Term of patent 7 years

(Cl. D62—4)

Fig. 1 is a front perspective view of an air conditioning cabinet, showing my new design; and

Fig. 2 is a rear perspective view of the same.

A portion of the cord is broken away in the figures for convenience of illustration only.

I claim:

The ornamental design for an air conditioning cabinet, as shown and described.
